UNITED STATES PATENT OFFICE.

OLMEDO CORTEZ WYSONG, OF GREENSBORO, NORTH CAROLINA.

SANDPAPERING-MACHINE.

996,443.

Specification of Letters Patent. Patented June 27, 1911.

Application filed July 12, 1909. Serial No. 507,197.

To all whom it may concern:

Be it known that I, OLMEDO CORTEZ WYSONG, a citizen of the United States, residing at Greensboro, in the county of Guilford 5 and State of North Carolina, have invented certain new and useful Improvements in Sandpapering-Machines, of which the following is a specification.

My invention relates to improvements in abrasive apparatus primarily for polishing straight work, and secondarily in provision for use of part of the mechanism for polishing irregular curved or straight work.

One of its objects is to provide mechanism 15 employing sand or abrasive belts to expeditiously polish large as well as small pieces of straight work, including the class of straight work heretofore treated on sand drums, such as doors, boards, window and door frames.

Another object is to provide mechanism whereby the abrasive belts successively act upon the work first at substantially right angles to the grain of the work, and then 25 substantially in line with the grain of the work.

Another object is to provide a single belt adapted to simultaneously act upon opposite sides of the work as it is fed forward, and 30 substantially in line with the grain of the work.

Another object is to provide improved means for guiding and holding the belts in contact with the work, and provision for 35 feeding the work continuously forward between the active sections of belt.

Another object is to make provision whereby the separate belts may be independently used when desired to polish 40 regular, curved or small pieces of straight work.

It further consists in certain details of form, combination and arrangement, all of which will be more fully set forth in the 45 description of the accompanying drawings in which:

Figure 1 is a top plan view of my improved mechanism. Fig. 2 represents in side elevation a modification of the forward 50 belts. Fig. 3 is a section on line $z-z$ of Fig. 1. Fig. 4 is a detail sectional view on line $v-v$ of Fig. 5. Fig. 5 is a front elevation of the mechanism of Figs. 1 and 3. Fig. 6 is a top plan view of a modification of the rear belt. Fig. 7 is a central vertical section illustrating a modification adapted to treat one 55 side of the work at a time.

In the accompanying drawings A represents the base or frame on which the operative parts are mounted.

A' represents a gib or way on which are mounted the standards B B', which are adjustable along said way by means of a screw b , to which the standards may be connected at will by means of a split nut or clutch b' 60 operated to open and close upon the screw by means of wedges b^2 actuated by eccentrics b^3 on the shaft b^4 . Thus the standards B B' may be fed to or from each other, or jointly to any position along the gib A'. 70 Swinging frames D D' are pivotally supported upon the standards B B' by means of hollow sleeves d , which serve as journal box for the shafts d' of the belt driving pulleys d^2 . The frames D D' also carry 75 adjustable idler pulleys d^3 , which serve to tension the abrasive belts d^4 d^5 and to make said belts track as desired over their pulleys, for which purpose said idler pulleys are mounted in yokes d^{12} the stems d^6 of which 80 are adjustable both endwise, and about their axes in sleeves d^7 , which sleeves are splined in sockets in the frames D D' and provided with rack teeth engaged by pinions d^8 by means of which said sleeves are quickly adjustable endwise. Set bolts d^9 d^{10} serve to lock the sleeves d^7 and stems d^6 to their adjusted positions.

E represents a support for the rear face of the working portion of the abrasive belt 90 d^4 . The support E is preferably provided with stud bolts e at its four corners by means of which the support can be adjusted relative to its supporting plate e' , the bolt e^2 serving to hold the support away from plate 95 e' near its center, thus permitting the support E to be adjusted by the bolts e and nuts thereon into any position required to align the belt d^4 . The plate e' is detachably supported upon a stud e^3 carried by the 100 frame D.

e^5 represents a table to support the work, which is detachably supported upon a stud e^6 carried by the frame D. The frame D is adapted to swing upon its pivotal support d 105 to any desired angle of adjustment, and to be locked in such adjusted position by means of a latch e^7 entering notches in the flange e^8 of frame D. The frame D' is angularly adjustable in the same manner as the frame D, 110 and has a work table e^5 . Its abrasive belt support E' is supported upon a plate e^9 and adjustable relative thereto in the same manner as the support E relative to plate e' .

The plate e^o is supported relative to frame D' by means of parallel links F F', which permits the plate e^o to be adjusted to and from the plate e' while preserving the alignment of its support E'. This adjustment is effected by means of a foot-lever f pivoted at f' to frame D' and provided with a crank arm f² and a link f³ to connect the crank arm with the plate e^o , so that pressure on the foot lever will advance the support E' toward the support E. Thus the two belts d⁴, d⁵ are adapted to be alined and employed conjointly to surface opposite sides of a single piece of work, as indicated in Figs. 1, 3, and 5, and also when adjusted a sufficient distance apart, or to different angles, to be used independently by different operators.

The belt pulleys d² driving the respective belts d⁴, d⁵ receive motion through separate pairs of cone gears f⁴, f⁵ the gears f⁵ being splined to the driving shaft f⁶, and held in mesh with the gears f⁴ by means of brackets f⁷ projecting from the standards B B'. The shaft f⁶ is adapted to receive motion by means of a belt through tight and loose pulleys f⁸, f⁹.

In order to provide for the rapid and efficient surfacing of large pieces of flat or straight work I preferably provide an abrasive belt G arranged in line with and in rear of the belts d⁴ d⁵, so that while the belts d⁴ d⁵ are adapted to work across the grain of the work, and to effect a rough surfacing of opposite sides thereof, the belt G will travel substantially in line with the grain of the work, or in a slightly diagonal line over the face of the work, to effect a finer and smoother finish of the work, which could not be effected by the use of either the belts d⁴ d⁵, or the belt G, alone.

The belt G is preferably supported upon a driving pulley g, and a series of idler pulleys g', g², g³. The pulley g³ is provided with a cushioned face, and the abrasive face of the belt runs thereon. Motion is imparted to the driving pulley g through an independent belt over the tight and loose pulleys g⁴ g⁵. The working sections of the belt G are supported in the rear by means of adjustable supports H H', the support H being carried upon a bracket h, which is adapted to be adjusted to the desired position and clamped by a clamping nut h'.

The support H' is carried by a bracket h² having a slotted opening h³, through which pass two stud bolts h⁴ to hold bracket h² in place and allow it a limited movement endwise. A spring h⁵ presses against the end of bracket h², and its tension is adapted to be regulated by means of a screw rod h⁶, to provide an automatically yielding tension of the support H' against the rear face of the belt G, to press the two working sections of the belt against the opposite faces of the

work. Supports H, H', are adjustable for alinement as described for support E. The tension of belt G is attained by shifting the frame g⁸ in which the pulleys g, g³ are journaled by means of the screw g⁹. The work 70 is supported between the supports H H' by means of a table h⁸, and the frame g⁸ is arranged low enough so that the work will pass from table h⁸ over the top of said frame. 75

Where it is designed to employ my improved mechanism exclusively in surfacing large pieces of straight work, a single abrasive belt K may be employed in place of the separate belts d⁴ d⁵, as indicated in Fig. 2, 80 said belt K being supported upon a driving pulley k and an adjustable idler pulley k' with its abrasive face toward said pulleys, and the working sections of the belt supported by supports k² k³, one of which is 85 adjustable either as described for the support H' or the support E'.

As a modification to be used in place of the belt G, I have illustrated in Fig. 6 two independent horizontal or substantially horizontal belts L L', the working sections of which are supported by supports N N' mounted and operated as described for the supports H H', said belts L L' being supported upon driving pulleys m m' and adjustable idler pulleys n n'. If desired the support E' may be mounted and tensioned as described for support H'. 90 95

As illustrated in Fig. 7, abrasive belts P P' having adjustable supports R R', preferably yieldingly tensioned, and corresponding to belts d⁵ and G of Fig. 1 are arranged to act successively upon one side only of straight work, the opposite side of the work being supported in contact with the active sections of said belts by means of table or support p, relative to which said belts and their supporting frames p', p² are adjustable. 100 105

In practice the belt sections traveling crosswise of the grain serve to rapidly abrade the surface, and to remove all inequalities, and produce a uniformly plane, but not smoothly polished surface, while the belt sections traveling with or substantially 110 with the grain of the work serve to highly polish such uniform surface, and to remove any marks caused by the previous belt sections traveling across the grain. 115

The mechanism herein illustrated and described is capable of considerable modification without departing from the principle of my invention. 120

Having described my invention, what I 125 claim is;

1. In a mechanism of the character described, a pair of abrasive belt sections adapted to contact with the opposite faces of the work and to travel at substantially right angles to the travel of the work, sup- 130

ports for the rear faces of said belt sections opposite the work, a pair of abrasive belt sections located in line with and in rear of said first named belt sections and adapted to travel substantially in line with the travel of the work, and supports for the rear faces of said last named belt sections opposite the work, and means to support the work.

2. In a mechanism of the character described, a support for the work, an abrasive belt adapted to contact with one face of the work, and to travel at substantially right angles to the travel of the work, a support for the rear face of said belt opposite the work, 10 an abrasive belt located in rear of said first named belt and adapted to contact with the work and to travel substantially in line with the travel of the work, and a support for the rear face of said last named belt opposite 15 the work.

3. In a mechanism of the character indicated, a substantially horizontal work support, a pair of vertically traveling abrasive belt sections located at opposite sides of said 25 work support, supports for the rear faces of said belt sections, a pair of substantially horizontally traveling abrasive belt sections located in rear of said first named belt sections and at opposite sides of said work 30 support, and supports for the rear faces of said last named belt sections.

4. In a mechanism of the character described, a substantially horizontal work support along which the work is adapted to be fed, an abrasive belt having an active section adjustable to and from the work support, said belt traveling at substantially right angles to the feed of the work upon 35 said work support, a support for the rear face of said active belt section, an abrasive belt located in rear of said first named belt having an active section adjustable to and from the work support and adapted to travel substantially in line with the feed of the 40 work, and a support for the rear face of the active section of said last named belt.

5. In a mechanism of the character indicated, a substantially horizontal work support, a pair of active abrasive belt sections 0 each traveling in a substantially vertical direction and adjustable to and from each other on opposite sides of said work support, supports for the rear faces of said active sections means to hold said active belt sections 5 yieldingly in contact with opposite sides of the work, a pair of active abrasive belt sections located on opposite sides of said work support, in rear of said first named belt sections, each adapted to travel in a substantially horizontal direction, supports for the 10 rear faces of said last named belt sections,

and means to hold said last named belt sections yieldingly in contact with opposite sides of the work.

6. In a mechanism of the character described, a substantially horizontal work table, a pair of abrasive belts adapted to travel in a substantially vertical direction, located upon opposite sides of said table and adjustable to and from each other, supports 65 for the rear faces of the active sections of said belts, and means adapted to yieldingly hold said active belt sections in contact with opposite sides of the work, a pair of abrasive belts located in rear of said first named 70 belts upon opposite sides of said work table and adapted to travel in a substantially horizontal direction, supports for the rear faces of the active sections of said last named 75 belts, and means adapted to hold said active 80 belt sections yieldingly in contact with opposite faces of the work.

7. In a mechanism of the character indicated, a base provided with ways, a pair of standards adjustable to and from each other 85 upon the ways of said base, pivotally supported frames mounted upon said standards and adjustable to various angles relative thereto, belt driving pulleys carried by shafts journaled within the pivotal supports 90 of said frames, adjustable idler pulleys carried by said frames and independent abrasive belts supported upon the pulleys of said respective frames, said belts being adapted to be used either conjointly upon a single 95 piece of work or separately upon different pieces of work.

8. In a mechanism of the character indicated, a base provided with ways, a driving shaft mounted in bearings carried by said 100 base, a pair of standards adjustable to and from each other upon the ways of said base, and provided with bearings supporting said driving shaft, adjustable frames pivotally mounted upon said standards, belt driving 105 pulleys carried by shafts journaled within the pivotal supports of said frames, gears carried by said pulley shafts in mesh with and receiving motion from gears splined to said driving shaft, adjustable idler pulleys 110 carried by said frames, and independent abrasive belts supported upon the pulleys of said respective frames, said belts being adapted to be used either conjointly upon a single piece of work or separately upon different 115 pieces of work.

In testimony whereof I have affixed my signature in presence of two witnesses.

OLMEDO CORTEZ WYSONG.
